UNITED STATES PATENT OFFICE.

WILLIAM S. PARKER, OF NEW YORK, N. Y.

ELECTRIC-ARC LAMP.

SPECIFICATION forming part of Letters Patent No. 269,453, dated December 19, 1882.

Application filed June 5, 1882. (No model.)

To all whom it may concern:

Be it known that I, WILLIAM S. PARKER, of New York city, New York, have invented a new and useful Improvement in Electric Lamps; 5 and I do hereby declare that the following is a full, clear, and exact description of the same, reference being had to the accompanying drawings, forming part of this specification.

My invention relates to the class of electric- 10 arc lamps in which the upper or positive carbon is controlled by a clutch actuated by one or more electro-magnets.

In all ordinary electric lamps in which the separation of the carbons to form or regulate 15 an electric arc is effected by the movement of an armature attracted by an electro-magnet the initial movement of the armature is necessarily slow and the further movement rapidly accelerated, owing to the well-known law 20 governing the action of magnets—that is, that the attractive power of a magnet is inversely as the square of the distance. The separation of the carbons by the attraction of a magnet in this class of lamps is, under all circum- 25 stances, secured by a variable force which is strongest when the arc attains its extreme length, owing to the forward movement of the armature in a magnetic field of rapidly-in- 30 creasing strength. In consequence of the pec- 35 uliar action of these magnets when the carbons separate to form the arc, or when they are moved in the operation of feeding, the variations in the arc are extreme, and as a result there is a great fluctuation in the light, as well 40 as a variation in its color. To obviate all these difficulties, I employ one or more magnets in which I use the repellent force instead of the attractive force. By this means I secure effects the reverse of those above described— 45 that is, I secure a quick separation of the carbons and a slower and less marked elongation of the arc by placing a polarized armature or core in a magnetic field of the same polarity, so that like poles are in opposition to each 50 other. In this way the core or armature of the regulating-magnet is in the strongest magnetic field when it makes its initial movement, and is quickly and forcibly repelled when the current is strengthened by the approach or con- 55 tact of the carbon, thereby raising the upper carbon very quickly, so as to instantly form the arc. This separation of the carbons di-

minishes the current, so that the repellent action of the regulating-magnet is rapidly weakened and the upward movement of the carbon ceases before the arc is sufficiently extended to yield a violet color or to diminish the light. The repelling-magnet, acting thus rapidly to form or lengthen the arc, renders the slight changes necessary to the feeding of the carbon unnoticeable and inappreciable, the movements of the upper carbon being practically instantaneous. In my improved electric lamp I may employ a single electro-magnet to control the upper carbon; or I may use two electro-magnets acting differentially, one of them being wound with coarse wire and the other with fine wire, the former being included in the arc-circuit and the latter in a derived or branch circuit. The cores of the magnets are 70 adapted to slide vertically, and are jointed to opposite ends of a vibrating lever. When the current becomes too strong by reason of the approximation of the carbons the magnetism of the soft-iron bobbin of the magnet in the main circuit is increased, so that said bobbin and its core become polarized in the same direction, and the core, being free to move, is consequently repelled out of the bobbin, and in such movement it acts on a clutch device 80 and raises the upper-carbon rod, thus separating the carbons and lengthening the arc.

The details of construction and operation are as hereinafter described.

Figure 1 is a horizontal section of a lamp 85 embodying my invention. Fig. 2 is a vertical section of a lamp with two regulating-magnets, and Fig. 3 is a vertical section of a lamp with a single regulating-magnet.

The lamp frame or case may be of any suitable form. On the plate A are fixed the differential magnets B C, the latter being the shunt-magnet. Both magnets are of the axial type, and are wound on tubular soft-iron bobbins containing the hollow soft-iron cores b c, 95 respectively. These cores are suspended by jointed links i i from opposite ends of a lever, d, suspended on a support, e, above the magnets.

D is the carbon-holder, and E is the clutch, 100 hung at only one end by a link, f, from the lever d above the lifting-magnet B. The clutch is made in two pieces, each forked at one end, the forked ends being connected by knuckle.

joints g , forming a jointed clutch, through which the carbon-holding rod D passes.

In the outer end of the clutch-bar a set-screw, h , is fitted to bear on the magnet C , so as to support the bar at that end.

The end of the lever d , supporting the core c of the shunt-magnet C , is connected to a spring, which tends to draw that end of the lever down and assist the rise of the lifting-core b . The two cores, being suspended from opposite ends of the lever, are both simultaneously moved by increase or decrease of magnetism in either magnet, and the combination forms a differential balance.

15 I provide for regulating the normal position of the core of the lifting-magnet B by fitting in the lower end of that magnet a pole-block, k , made as a screw-plug, that can be set in and out of the magnet.

20 The action of the core, lever, and clutch mechanism is due to the repulsive action of the cores and surrounding bobbins in this wise: When the current becomes too strong by reason of contact of the carbons or shortness of the 25 arc the magnetism of the coil B is increased and the iron bobbin and core become polarized in the same direction, which, upon a well-understood principle, results in the expulsion or upward movement of the core b . This action 30 of the latter tilts the lever d , thus causing the clutch-lever E to grip the carbon-holding rod D and raise it, so that the carbons will be separated and the arc elongated, as required, and when such separation of the carbons has increased the resistance to the passage of the 35 current to a sufficient degree the branch circuit polarizes the iron bobbin of the shunt-magnet C throughout its whole length, so that both ends repel the adjacent ends of the iron 40 core c , thereby moving the lever d back to its original position, which causes a release of the clutch g and allows the carbon rod D to drop far enough to reduce the resistance of the arc to its normal condition.

45 In some cases I disconnect the shunt-magnet from the circuit or dispense with it altogether, as in Fig. 3. With this arrangement

the main-circuit magnet B alone is employed, its repellent force lifting the carbon-holder as the current increases, the diminution of the 50 repellent force permitting the carbon-holder to descend of its own gravity. In some cases I may employ the core c or weight c' as a counter-balance to oppose the weight of the carbon rod D .

55

The repelling-magnet is peculiarly adapted to the control of the electric arc, readily releasing the carbon-holder in case of the weakening or interruption of the current, so as to allow the upper carbon to approach or touch the 60 lower one. It gives a very quick initial separating movement to the upper carbon, so as to form the arc in an inappreciable space of time, and at the same time prevents an undue separation of the carbons by a rapid diminution of 65 the movement of the carbon and a final stop at the maximum length of arc.

What I claim as new is—

1. In an electric lamp, the combination, with the carbon-holder, of one or more repelling 70 electro-magnets and suitable connecting mechanism, substantially as herein shown and described, whereby the carbon will be moved and governed by the repellent action of the magnet or magnets, as set forth.

75

2. The combination of the magnets B C , formed of soft-iron bobbins, wound respectively with coarse and fine wire, and included in the main and branch circuit, as specified, the soft-iron cores b c , vibrating lever d , a clutch 80 device, and the carbon-holding rod D , all as shown and described, whereby increase of magnetism of coil B causes the core b and its surrounding bobbin to become polarized in the same direction, so that said core is repelled.

85

3. The combination, with electro-magnet B and its core b , adapted to move freely, of the adjustable stop piece or block k , inserted in the lower end of said magnet, as shown and described.
